UNITED STATES PATENT OFFICE.

LOUIS E. SADLER, OF ATTLEBORO, MASSACHUSETTS, ASSIGNOR TO THE F. H. SADLER COMPANY, OF ATTLEBORO, MASSACHUSETTS.

DISPLAY EASEL.

1,419,944.

Specification of Letters Patent. Patented June 20, 1922.

Application filed November 15, 1921. Serial No. 515,234.

To all whom it may concern:

Be it known that I, LOUIS E. SADLER, a citizen of the United States, residing at Attleboro, in the county of Bristol and State 5 of Massachusetts, have invented new and useful Improvements in Display Easels, of which the following is a specification.

This invention relates to certain new and useful improvements in display easels and 10 pertains more particularly to an easel employed for displaying or exhibiting belts used for personal wear.

The primary object of the invention is to provide an easel which is formed to display 15 a number of belts and wherein the belts are held in a manner permitting of same being easily and quickly removed from and secured to the easel.

A further object of the invention is to 20 provide an easel which displays the belts effectively and to the best advantage and wherein the belts are held in place solely by or through frictional engagement with the belt-receiving parts or pockets.

25 The invention still further aims to provide an easel structure which is attractive and of simple and economical construction and also one devoid of all moving parts, while still holding the belts in an efficient manner.

In the drawings:

Figure 1, is a perspective view of the invention; and

Figure 2, is a transverse section.

35 In proceeding in accordance with the present invention, a body 1 is employed having a suitable leg or support 2 so as to hold the body at an incline. The body is formed with a series of transverse pockets or compartments 3 arranged in spaced relation and each extending through the respective opposite sides of the body as clearly depicted in Figure 2 of the drawings. The front of the body as well as the sides, and the ends 45 of the pockets, may be covered with suitable fabric 4, such as plush or velvet or other material, as desired.

In use the belt B has its ends connected to the buckle as in actual use, whereupon the 50 front and rear portions of the belt are

brought into engagement and the ends of the resultant formation are then turned or folded inwardly and engaged with the side edges of the body and inserted in the respective ends of one of the pockets or compartments, with the buckle and central parts of the belts disposed on the outer face of the body. The pockets or compartments are formed at their ends so as to effect a frictional fit with the inturned belt portions 55 sufficient to hold the latter in place without the use of any extraneous fastening, thus providing a simple and economical construction and at the same time, one allowing of the belts being easily and quickly applied 60 to and removed from the easel. The belt is thus held at the ends thereof resultant from folding or doubling of the belt upon itself, since the normal ends of the belt are connected by the buckle, as in actual wear or 65 use of the same. The intermediate parts of the doubled belt extend across the front of the body at points alined with the longitudinal axis of the pocket, and accordingly the body is made of a width to afford display of a considerable part of the belt and to also necessitate inturning of but sufficient of the end portions to effect 70 securing of the belt in position.

Having thus described my invention, what 80 I claim as new and desire to secure by Letters Patent is:—

In a display easel for belts, a body having a belt supporting central part, and a pocket in each side of the body, said pockets 85 being spaced apart at such distance so as to receive the doubled ends of a belt therein, said pockets having spaced front and rear walls to provide abutments against which the doubled ends of a belt are adapted to 90 frictionally press to hold the central part of a belt in position.

In testimony whereof I have signed my name to this specification in the presence of two subscribing witnesses.

LOUIS E. SADLER.
